(57) **CLAIM**

The ornamental design for a material conveying groove, as shown and described.

DESCRIPTION

FIG. 1 is a front view of a material conveying groove showing our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a perspective view thereof;

FIG. 8 is another perspective view thereof;

FIG. 9 is another perspective view thereof;

FIG. 10 is another perspective view thereof;

FIG. 11 is another perspective view thereof; and,

FIG. 12 is another perspective view thereof.
